UNITED STATES PATENT OFFICE.

EDMUND M. BENDHEIM, OF NEW YORK, N. Y.

APPARATUS FOR REPAIRING MOTION-PICTURE FILMS.

1,264,362.

Specification of Letters Patent. Patented Apr. 30, 1918.

Application filed July 5, 1917. Serial No. 178,536.

To all whom it may concern:

Be it known that I, EDMUND M. BENDHEIM, a citizen of the United States, and a resident of New York city, in the county 5 and State of New York, have invented certain new and useful Improvements in Apparatus for Repairing Motion - Picture Films, of which the following is a specification.

10 This invention relates to an apparatus of novel construction for repairing a motion picture film, by cutting out a portion of the film, preparing the ends of the two severed sections, overlapping said ends, and cementing such ends to each other. With an apparatus of this kind, the greatest accuracy is required, any shifting of the film sections is to be avoided, and an exact alinement of the perforations in said sections is 15 to be obtained. By my invention, all these conditions are complied with, buckling of the film is prevented, and a joint of great strength and smoothness is obtained, so that the joined negative film may be fed through 20 a printing machine, or the repaired positive film may be run through a projector at the great speed required during the printing or displaying of the pictures.

The invention comprises the various features of novelty more fully pointed out in the specification and appended claims.

In the accompanying drawings:—

Fig. 1 is a plan view of an apparatus embodying my invention with the clamp 30 and cutter head bearings in section;

Fig. 2, a plan with the clamps and cutter head lowered;

Fig. 3, a cross section on line 3—3 Fig. 1;

Fig. 4, a cross section on line 4—4 Fig. 1;

40 Fig. 5, a longitudinal section on line 5—5 Fig. 2;

Fig. 6, a section on line 6—6 Fig. 8;

Fig. 7, a cross section on line 7—7 Fig. 1;

Fig. 8, a section on line 8—8 Fig. 2;

45 Fig. 9, a horizontal section through the cutter head;

Fig. 10, a section on line 10—10 Fig. 5;

Fig. 11, a front elevation of the apparatus, with the cement pots broken away;

50 Fig. 12, a portion of the film after being cut;

Fig. 13, a portion of the film with the severed portion removed, and the underlying section scraped;

55 Fig. 14, a bottom view of the overlying section showing it filed;

Fig. 15, shows the film after being repaired;

Fig. 16, is a section on line 16—16 Fig. 1;

Fig. 17, a detail of one of the cutting 60 blades;

Fig. 18, a detail of one of the alining teeth, and

Fig. 19, a detail of the scraper blade.

The apparatus comprises a frame 1 sup-

ported on legs 2, and provided with a top

plate or table 3, secured to the frame by

screws 4, said table forming part of the

frame. From one half of the table, prefer-

ably the left half, project upwardly two 70

rows of parallel fixed bosses or pins 5 adapt-

ed to engage the conventional perforations

extending along the rims of the positive or

negative film to be repaired or joined, said

half of the table being near its inner end 75

provided with a downwardly inclined sec-

tion or dip 6. At the end of this inclined

section, there is affixed to a bed plate 7 which

is secured to table 3 by screws 4 and 8, and

forms part thereof, a horizontal, trans-

versely extending preferably reversible

shearing member 9, coacting with one of

a pair of cutting blades hereinafter referred

to. To the right of shearing member 9, table

3 is provided with a transversely extending 80

depression 10 that is flush with said member

and thence slopes upwardly from left to

right. The right half of table 3 supports a

longitudinally movable slide or platen 11,

furnished with two rows of parallel bosses

described, the lever is furnished with a resilient shank, that adapts it to be sprung into either one of a pair of notches 20, 21 formed in frame 1, and connected by a transverse slot 22, having beveled upper and lower edges, the correlation of the parts being such, that the position of the notches is coincident with the terminal positions of slide 11. The latter is held to its course, during its movement by a pair of outer L shaped guides 23 and a central T shaped guide 24, depending from the slide, and extending through longitudinal slots 25, 26 of table 3. Lever 13 rests in all of its positions, upon a fixed bridge support 27, extending along the bottom of frame 1 and forming part thereof, the construction of the platen and of its operating mechanism being such, that the platen is at all times held against lateral or vertical displacement. At the left hand end of the raceway of platen 11, there is provided a transversely movable preferably reversible file 28 having an upper roughened face which is adapted to roughen and clean the underside of the overlying or right hand portion of the film to be patched, along its left hand edge, the inner edge of said file constituting a shearing member that coacts with the second of the cutting blades herein-after referred to. File 28 is sunk in a slot of table 3, so that its surface is flush with that of the table, and is affixed by screws 29, to a slide or movable base 30 supported on bed plate 7 and furnished at its ends with fingers 31, that extend into an opening formed between table 3 and bed plate 7, said fingers constituting guides during the movement of the slide. In order to reciprocate slide 30 and consequently file 28, in the transverse direction desired, i. e. at right angles to the rows of bosses 5, 12, it is furnished with a depending pin 32 which extends through an aperture 33 of plate 7. This pin engages a ratchet, or actuating eccentric member 34, having a zigzag groove and secured by screws 35 to a longitudinally movable slide 36 which is supported on bridge 27 and is provided with a right hand lower extension 36^a adapted to be guided on bridge 27 by means of a feather 37 and a groove 38. Slide 36 is operated by a lever 39 pivoted to frame 1 at 40 and having an elongated slot 41, engaged by a pin 42 that extends through and projects below the slide. The latter is provided at its left hand end with an upward extension 36^b which is T shaped in cross section and is guided within a longitudinal slotted raceway 43 of plate 3, said extension being sunk slightly below the level of the table. By the means described, the slide is so guided during its movement both at its bottom and top, that vertical and lateral play is obviated, and a true restricted rectilinear movement is insured. Lever 39 is bipartite, its two members being connected by means

of a flat spring 44 which renders it flexible. Spring 44 is attached to the inner member, by means of screws 45 that likewise serve to secure a pair of upper and lower slotted plates 46 and 47 to said member, the slots in said plates being alined with slot 41 and constituting reinforcements for the latter. The outer end of the spring enters a slot formed in the outer member or handle of lever 39, to which it is attached by a screw 48. Lever 39 plays within a clearance formed between slide 36 (to the left of extension 36^a) and bridge 27, and protrudes through a slot 49 formed in frame 1 said slot having upper and lower beveled edges. This slot opens at 80 its left end into a notch 50, into which the lever 39 may be sprung, so as to thereby lock slide 36 in its retracted position. It will be seen that by manipulating the lever, slide 36, and consequently eccentric 34, will be longitudinally reciprocated, and that thereby the desired transverse reciprocating movement is imparted to the slide 30 (and consequently to file 28) by means of pin 32.

Between the inner shearing edges of members 9 and 28, there is mounted on table 3, between depression 10 and the right hand slope thereof, a pair of transversely alined teeth 51 (Fig. 18) which are of triangular form in cross section, each tooth having a pair of flat parallel sides 51^a an inclined edge 51^b facing slide 11, and a vertical edge 51^c facing the left hand or fixed portion of the table. Teeth 51 are likewise centered between the two cutting blades hereinafter referred to and are alined longitudinally with the bosses 5 and 12, so that by projecting the teeth through perforations in the damaged or other part of the film, to be removed, the film will be centered so that the proper cut will be insured. By providing the teeth with inclined right hand edges, the edge and the sprocket holes of the right hand portion of the severed film, will during the subsequent inward movement of slide 11, be enabled to ride freely over the teeth, so as not to become caught thereby. Besides assuming the function of properly locating the cut, teeth 51 by engaging perforations in the right hand portion of the severed film, assume the additional function of locking said portion in position after the same has been lapped over the left hand portion, and while the seam is being cemented. In proximity to teeth 51 there is provided, an ejector 52 which has for its purpose to lift the discarded part of the film from the table, and assumes the additional function of raising, whenever necessary, the right hand section of the film off the table to an extent sufficient to clear the teeth. This ejector is shown to consist of a substantially U-shaped length of wire turning in a rear bearing 53, and a front bearing 54, which is slotted for permitting the assemblage of the parts. 130

The main longitudinal section of this wire is sunk into the table so as to be flush therewith, while the two transverse sections are received within table slots, that slope downwardly from right to left. The forward end of the ejector protrudes beyond frame 1, and carries a handle 55, that holds the ejector within bearing 54, and permits it to be manipulated. A spring 56 coiled around 10 the handle and secured thereto at one of its ends, while the other end is secured to a fixed support, returns the ejector to its normal inert position after having been released. In order to limit the upward throw 15 or rotation of the ejector, it is furnished with a pin 57, adapted to strike a stop 58, as soon as the ejector has been raised to its maximum extent.

To the back of frame 1, there is hinged, a 20 pair of clamps 59, 60, and an interposed cutter head 61, said clamps and cutter head turning on a tapered pintle 62, which is threaded into bearings 63, and carries a nut 64.

Clamp 59 when lowered, coincides at its right hand edge with the right hand edge of inclined section 6, so that it clears shearing member 9 and defines the location of the scraper blade coacting therewith, and hereinafter referred to. Within the top of clamp 59 is formed a longitudinal slot 65, which is preferably circular in cross section. Within this slot is free to move a guide rod 66 to which is affixed by a screw 67, a dovetailed head 68, the whole constituting a slide which is operated by the head of screw 67, that constitutes a handle. Head 68 engages the beveled top of clamp 59 and carries a slotted holder 69, into which is fitted, a reversible, flexible and adjustable scraping blade 70 (Fig. 19) having beveled upright edges one of which engages squarely, the adjacent side of clamp 59. This blade is reciprocable directly above shearing member 9, and is set at an incline to the plane of the film and also obliquely across the surface to be scraped. The play of the slide is limited by a pair of back stops 71 and by a front stop 72 which is engaged by the head 68 of said slide. As shown, clamp 59, is bipartite, being furnished with a lower section 59^a, which is secured to the main section of the clamp by screws 73, in such a manner as to form an intervening clearance 74. Within 55 this clearance is accommodated a locking lever or member 75, fulcrumed at 76, and adapted to be projected beyond the right hand side of clamp 59, so as to engage and lock a presser foot hereinafter more fully referred to. The bottom of lower section 59^a has a dip from left to right, coinciding with dip of inclined depression 6, and is mortised as at 77, so as to clear the bosses 5 that are covered by the clamp. Right hand lugs 78 engaging corresponding

notches 79 of member 59^a in conjunction with left hand lugs 80, engaging the left hand end of said member, hold the clamp against lateral and longitudinal displacement. The backward throw of clamp 59 is limited by a stop 81, while the clamp may be locked to the table in its lowered position by a catch 82.

Clamp 60 is provided with a pair of grooves 83 extending transversely across its bottom and adapted to accommodate bosses 12. To clamp 60 is hinged at 84 a presser foot 85, which is retracted by a spring 86 and may be swung longitudinally of table 3, the presser foot being of such a length that when swung down, its free end comes to lie squarely against the right side of clamp 59. This free end of the clamp is turned down to form a head which carries on its under face, a pair of pins 87 adapted to be passed through the aligned sprocket holes of the overlapped film sections, and to thence enter mortises 88 of shearing member 9 whereby any displacement of said overlapped sections is prevented. The upper face of the presser foot head is arched transversely as at 89 and this head is, in the lowered position of the presser foot, adapted to be engaged by lever 75, which when swung over the same, forces the presser foot tightly against the overlapped film portions so that the latter are held in close contact while being cemented together. Clamp 60, is similar to clamp 59, provided with a stop 90 that checks its back throw, and with a catch 91 by means of which it is locked to the table when in its lowered position. Lugs 92 and 92^a on table 3 which are adapted to enter notches formed in the sides of clamp 60 hold the same against lateral and longitudinal displacement.

The cutter head 61 is so hung to the table that the teeth 51 will be centered within its sweep. It is mounted on a base 93 which has a lower flare coincident with the depression 10 of table 3 and is furnished with the back stop 94, and a catch member 95 adapted to engage a corresponding member 96 on frame 1. The left side of cutter head base 93 engages the right hand side of lugs 78 while notches in the right hand side of base 93 are engaged by lugs 92^a by which construction all lateral and longitudinal play of the cutter head is prevented. On base 93 is mounted a square frame composed of a pair of open rectangular side plates 97, a pair of end plates 98, and a top plate 99, said parts being connected to base 93 and to each other, by tongues and mortises and also by screws 100 that pass through said parts and are tapped into the base, while furthermore tenons 101 extending from the side and end members enter corresponding mortises of the base and top. Within the frame constructed as described, is vertically recip-

rocable, a knife carrier or block 102 which is guided within the frame by means of tongues 103 engaging corresponding grooves of end plates 98. The knife carrier is operated by means of a double thread screw 104 having a long pitch and threaded into top plate 99. The lower end of screw 104 carries a disk 105 rotatable within block 102, and furnished with a centering pin 106 entering the block. Screw 104 is held to the block by means of an annulus 107 through which it passes, and which is fastened to the block in suitable manner. To the upper end of screw 104 is keyed a winged nut 108, by means of which it may be turned. Against both faces of block 102 are placed cutting blades 109 (Fig. 17) the lower ends of which pass through the cutter heads, and are adapted to enter grooves 110 formed within table 3, said grooves extending along the inner edges of shearing member 9 and file 28, so that in this way, the blades coact respectively with said edges to make the required two transverse parallel cuts across the film. Each cutting blade is provided with outwardly flaring ends, and with a V-shaped lower working edge 111, which is preferably duplicated at its upper edge so as to render the blade reversible. The V-shaped cutting edge which on lowering will be centered between the two rows of bosses of table 3, will first puncture the center of the film (where the film is strongest) and will thence extend the cut gradually toward the two edges of the film (where the film is weakest, owing to the presence of the sprocket holes) so that a clean transverse cut is obtained, and any tearing along the edges of the film is prevented. The two blades 109 which are spaced by block 102, in the manner described, are shown to be removably connected to the latter by means of a clamp 112, carrying a number of prongs 113 that pass through aligned openings of said blades and block. The protruding end of one of these prongs is threaded for the reception of a winged nut 114 that is centered within the opening of that side plate 97, which faces clamp 60. In this way, the nut is readily accessible for clamping the blades 109 to the block 102, and for removing them therefrom.

Table 3 is provided at its two rear corners with apertured extensions 115 (Fig. 16) adapted to receive wells or bottles 116 one of which contains cement while the other contains a prepared alkaline water. Each bottle has a threaded neck, engaged by an apertured threaded cap, by means of which the bottle is suspended. The bottles are furnished with plugs 118, through which pass brushes or similar applying devices 119.

The operation is as follows:—

The film 120 (Fig. 12) to be repaired is placed upon the table in such a manner that

the portion 121 to be removed, is engaged by the centering teeth 51 while the left and right portions of the film are engaged respectively by the fixed bosses 5 and the movable bosses 12 of slide 11. Both clamps 59 and 60 are lowered and locked to the table, whereby the clamp 59 owing to its bottom dip and the coöperating inclined table section 6, will force the intervening film section downward, so that that portion which extends beyond the right hand edge of clamp 59 will be gradually depressed. Section 122 which overlies shearing member 9 is moistened with an alkaline water, and slide 66, 68 is manipulated to reciprocate blade 70 over said section 122, thereby removing the sensitized emulsion and the gloss. The blade is so set as to be flush with the depressed section 10 of table 3, so that, at the ends of its stroke (or in its inert positions) it will be, by the slightly raised surface of the table, placed under tension, which is maintained by the blade during its movement over the section 122 of the film supported on shearing member 9. The rear edge of depression 10 is set on an oblique angle to the axis of the table, (Fig. 1), so that in this way, the blade may readily ride from the table surface onto said section 122. The cutter head 61 is lowered upon the table and locked, the lower flare on base 93 serving to hold the film taut during filing and cutting, the slide 36 is manipulated by handle 39, to reciprocate file 28 along the under side of the film section 123 which overlies said file, whereby the latter is cleaned and roughened. Screw 104 is turned to lower blades 109 and thus cut out section 121 between the previously prepared sections 122 and 123, and then the screw is turned in the opposite direction to raise the blades. The cutter head is thrown back, and the ejector 52 is raised to correspondingly elevate the severed section 121, and thus facilitate its manual removal. Lever 13 is swung through part of its course to bring the edge of right hand film section 124 against teeth 51. Cement is applied to the scraped section 122, ejector 52 is again manipulated to assure the free passage of section 124 over teeth 51, and lever 13 is swung through the balance of its path, whereby slide 12 will advance section 124, to such an extent, that section 123 will overlie section 122. The ejector 52 is released and presser foot 85 is swung down and locked by lever 75, whereby sections 122 and 123 are tightly pressed against each other while the cement is setting to make joint 125. After the cement has set, lever 75 is swung back, to release presser foot 85, the latter is thrown up by spring 86, and both of clamps 59 and 60 are opened, which completes the operation.

I claim:

1. A film repairing apparatus compris-

- ing a table, a shearing member and a transversely movable file carried thereby, said file having an upper roughened face adapted to engage the lower side of the film and 5 a cutter head having a pair of spaced cutting blades adapted to coöperate respectively with said shearing member and said file.
2. A film repairing apparatus comprising 10 a table, having a series of fixed bosses, a slide having a series of bosses alined with the first named bosses, an interposed shearing member and file, said file having an upper roughened face adapted to engage the 15 lower side of the film and a pair of cutting blades coöperating respectively with said shearing member and file.
3. A film repairing apparatus comprising 20 a table, having a series of fixed bosses, a slide having a series of bosses, an ejector interposed between the fixed bosses and the slide front and rear bearings in which said ejector is adapted to turn, said ejector being provided with a U-shaped section intermediate said bearings.
4. A film repairing apparatus comprising 25 a table having a series of fixed bosses, and a series of movable bosses, a pair of members mounted on the table between said fixed bosses and movable bosses, said members having shearing edges, a pair of cutting blades coöperating with said shearing edges, and a pair of alined teeth that project upwardly from said table and are centered between said shearing edges.
5. A film repairing apparatus comprising 30 a table having a series of fixed bosses, a slide having a series of bosses, a pair of centering teeth mounted on the table and interposed between the fixed bosses and the 35 slide; and an ejector journaled in the table in proximity to said teeth.
6. A film repairing apparatus comprising 40 a table, fixed bosses on one side of the table, a slide on the other side of the table, said slide having additional bosses, a shearing member and a file interposed between the fixed bosses and the slide, said file having an upper roughened face adapted to 45 engage the lower side of the film, a centering tooth and an ejector interposed between the shearing member and the file, and a pair of cutting blades coöperating with the shearing member and the file respectively.
- 55 7. A film repairing apparatus comprising a table, fixed bosses on one side of the table, a slide on the other side of the table, said slide having additional bosses, a shearing member and a file interposed between the 60 fixed bosses and the slide, said file having an upper roughened face adapted to engage the lower side of the film, a pair of beveled teeth and an ejector interposed between the shearing member and the file, a scraper coöperating with the shearing member, and a pair of 65 cutting blades coöperating with said shearing member and the file respectively.
8. A film repairing apparatus comprising 70 means for scraping a section of a film transversely along its upper side, means for filing a section of said film transversely along its lower side, means for cutting the film between its scraped section and its filed section, and means for superimposing said filed section over said scraped section.
9. A film repairing apparatus comprising 75 means for centering a film, means for scraping a section of the film transversely along its upper side, means for filing a section of the film transversely along its lower side, 80 means for cutting the film between its scraped section and its filed section, means for ejecting the severed portion of the film, and means for superimposing the filed section over the scraped section.
10. A film repairing apparatus comprising 85 a table having an inclined section adapted to support a portion of a film, a slide adapted to support a different portion of said film, said slide being arranged at a higher level than the lower part of the inclined section, and means for cutting the film intermediate said inclined section and said slide.
11. A film repairing apparatus comprising 90 a table having an inclined section, a shearing member at the bottom of said inclined section, a slide arranged at a higher level than said shearing member, a file reciprocable laterally between the shearing member and the slide, and a pair of cutting blades coöperating respectively with said shearing member and file.
12. A film repairing apparatus comprising 95 a frame having rows of fixed bosses, and rows of movable bosses, a file interposed between said fixed bosses and movable bosses, said file having an upper roughened face adapted to engage the lower side of the film and means for imparting a movement to the 100 file transversely to said row of bosses.
13. A film repairing apparatus comprising 105 a frame having rows of fixed bosses, and rows of movable bosses, a transversely movable file interposed between said fixed bosses and movable bosses, said file having an upper roughened face adapted to engage the lower side of the film, a member depending from the file, an eccentric engaging said member, and a longitudinally movable slide carrying 110 the eccentric.
14. A film repairing apparatus comprising 115 a frame, a transversely movable slide, means for guiding said slide across the frame, a file carried by the slide, a pin depending from the slide, a longitudinally movable slide, and an eccentric member having a zig-zag groove engaged by said pin.
15. A film repairing apparatus comprising 120 a frame having a slot, a file adapted to 125

reciprocate across said frame, a longitudinally movable slide adapted to actuate said file, said slide having a lower extension which is guided on the frame and an upper 5 T-shaped extension, that engages said slot.

16. A film repairing apparatus comprising a frame, a file reciprocable across said frame, a longitudinally movable slide operatively connected to said file, said slide having 10 a lower extension which is guided on the frame and a clearance sidewise of said extension, and a lever operatively connected to the slide and received within said clearance.

17. A film repairing apparatus comprising 15 a frame having a slot and a communicating notch, a file reciprocable across said frame, said file having an upper roughened face adapted to engage the lower side of the film, a longitudinally movable slide operatively connected to said file, a bipartite lever pivoted to the frame and operatively connected to the slide, said lever having an inner member pivoted to the frame, an outer member adapted to engage said slot and 25 notch, and a spring connecting said inner member to said outer member.

18. A film repairing apparatus comprising a frame, two rows of fixed bosses, and two rows of movable bosses carried thereby, 30 and a pair of centering teeth interposed between said fixed bosses and movable bosses, said teeth having a pair of flat sides and being provided with inclined edges that face the movable bosses.

35 19. A film repairing apparatus comprising a frame, two rows of fixed bosses, and two rows of movable bosses carried thereby, and a pair of centering teeth interposed between said fixed bosses and movable bosses, said teeth having a pair of flat sides, upright edges that face the fixed bosses and inclined edges that face the 40 movable bosses.

20. A film repairing apparatus comprising 45 a frame having a groove, two rows of fixed bosses and two rows of movable bosses carried by said frame, and a U-shaped ejector pivoted to said frame intermediate said fixed bosses and movable bosses, and adapted 50 to engage said groove.

21. A film repairing apparatus comprising a frame, two opposed sets of bosses carried thereby, a U-shaped ejector pivoted to said frame intermediate said sets, a spring 55 engaging said ejector, and means for limiting the rotation of the ejector.

22. A film repairing apparatus comprising 60 a frame, a longitudinally slotted clamp hinged thereto, said clamp having a beveled top, a guide rod movable within the slot, a dovetailed head guided on said beveled top, a headed screw connecting said guide rod to said head, a holder carried by the head, and a scraping blade engaging 65 the holder.

23. A film repairing apparatus comprising a frame having an inclined section, a shearing member mounted on the frame at the bottom of said inclined section, a clamp hinged to the frame and having an inclined 70 bottom coincident with the dip of said inclined section, and a scraping blade carried by the slide and adapted to coöperate with said shearing member.

24. A film repairing apparatus comprising 75 a frame, a first clamp hinged thereto, said clamp being formed of an upper section and a lower section which is spaced from the upper section to form a clearance, a locking lever pivoted to said clamp within 80 said clearance, a second clamp hinged to the frame, and a presser foot hinged to said second clamp and adapted to be engaged by said locking lever.

25. A film repairing apparatus comprising 85 a frame having an inclined section, a first clamp hinged thereto, said clamp being formed of an upper section and a spaced lower section, said lower section having an inclined bottom that coincides with said inclined 90 frame-section, a slide carried by the upper section, a scraping blade carried by the slide, a locking lever pivoted to the clamp intermediate its upper and lower sections, a second clamp hinged to the frame, and a 95 presser foot hinged to said second clamp and adapted to be engaged by said locking lever.

26. A film repairing apparatus comprising 100 a frame, an apertured shearing member carried thereby, a clamp hinged to the frame, a presser foot hinged to the clamp, said presser foot having pins adapted to engage the apertured shearing member.

27. A film repairing apparatus comprising 105 a frame, a first clamp hinged thereto, a locking member fulcrumed to said clamp, a second clamp likewise hinged to the frame, and a presser foot hinged to said second clamp, said presser foot having an 110 arched head adapted to be engaged by said locking member.

28. A film repairing apparatus comprising 115 a table having two rows of bosses, a pair of clamps adapted to be projected across the table over said bosses, a scraper carried by one of said clamps, a cutter head movable relatively to the table, and a pair of spaced cutting blades carried by the cutter head, said blades having V-shaped cutting edges, 120 that are adapted to be projected transversely across said rows of bosses.

29. A film repairing apparatus, comprising 125 a table having two rows of bosses, a pair of clamps adapted to be projected across the table over said bosses, a scraper carried by one of said clamps, a cutter head hinged to the table, and a pair of spaced reversible cutting blades carried by the cutter head, said blades having a pair of V-shaped cut- 130

ting edges, and being adapted to be projected transversely across said rows of bosses.

30. A film repairing apparatus comprising a table having film retaining means, a pair of 5 clamps adapted to be projected across the table over said film retaining means, a scraper carried by one of said clamps, a cutter head hinged to the table and having a pair of open 10 sides, a carrier movable within the cutter head, and a pair of spaced parallel blades secured to the carrier.

31. A film repairing apparatus comprising a table having film retaining means, a pair 15 of clamps adapted to be projected across the table over said film retaining means, a scraper carried by one of said clamps, a cutter head hinged to the table and having a pair of open sides, a carrier slidable within 20 the cutter head, a pair of spaced blades movably secured to the carrier, and a screw tapped into the cutter head and engaging the carrier.

32. A film repairing apparatus comprising a table having film retaining means, a pair 25 of clamps adapted to be projected across the table over said film retaining means, a scraper carried by one of said clamps, a cutter head having open sides and hinged to the table, a carrier, means for guiding the 30 carrier within the cutter head, a screw tapped into the cutter head and engaging the carrier, a pair of parallel blades having V-

shaped cutting edges, and a clamp for securing said blades to opposite sides of said carrier.

33. A film repairing apparatus comprising 35 a table, having fixed bosses, a slide carried by the table and having alined bosses, a centering tooth and an ejector, intermediate the fixed bosses and the slide, a pair of 40 clamps hinged to the table, a presser foot hinged to one of said clamps, a coacting locking member carried by the other clamp, a cutter head hinged to the table intermediate the clamps, and a pair of spaced cutting 45 blades carried by the cutter head.

34. A film repairing apparatus comprising a table having a depression, a shearing member sunk into the table flush with said depression and adapted to support a film section, a clamp hinged to the table, a slide carried by the clamp and a resilient blade carried by the slide, said blade being adapted to be passed obliquely from the surface of the table over said film section, whereby said 55 blade is placed under tension.

35. A film repairing apparatus comprising a table having an inclined section, a file flush with the table, and a cutter head hinged to the table and having a flaring base which 60 is adapted to engage the inclined table section.

EDMUND M. BENDHEIM.
